UNITED STATES PATENT OFFICE.

CARL ZIMMER, OF SCRANTON, PENNSYLVANIA.

DEVICE FOR WAVING HAIR.

Application filed January 11, 1928. Serial No. 245,951.

This invention relates to improvements in hair curlers, particularly of the type which may be used for holding and curling the hair to produce permanent hair waves.

5 An object of this invention is to provide a permanent hair waver and curler, which will eliminate many of the disadvantages found in devices for curling hair now in common use, such as the use of the ordinary 10 disc-shaped hair pincher in co-operation with a hair curling pin, the pin being screwed into the pincher, thereby making it difficult and inconvenient to apply and remove the device without consuming a great 15 deal of valuable time and after many manipulations.

A further object of this invention is to provide a device for producing permanent hair waves which will be simple in operation 20 owing primarily to the fact that the pincher member may be entirely removed from contact with the hair and curling pin element after the hair strands have been properly positioned around the curling pin, 25 the removal of the pincher member functioning to leave the hair still positioned or curled around the pin, after which the pin may be easily removed from contact with the hair without the usual annoyance to the parties being treated, as well as excessive 30 labor on the part of the operator. In a hair curling device of the usual type, it is always difficult, laborious and annoying to be obliged to unscrew the curling pin from 35 the hair pincher before the hair can be removed from the pin.

Other objects of this invention will appear from the following detailed description of the device and as disclosed in the single 40 sheet of drawings which is herewith made a part of this application.

In the drawings—

Figure 1 illustrates a perspective view of the permanent hair waver disclosing the 45 pincher and hair curling pin in assembled and operative relationship.

Figure 2 represents an elevational view of the permanent hair waver disclosing the general location of the hair pinching disk in 50 assembled relationship with the curling pin.

Figure 3 illustrates a side elevational view of the device for waving hair.

Figure 4 illustrates the end elevational view disclosed in Figure 2 by showing the movable discs in clamped and operative relationship with strands or hair. 55

Figure 5 illustrates an end elevation view of the permanent hair waver taken along line 5—5 of Figure 3, showing with the curling pin and the discs to which the pin is attached removed, thereby disclosing the movable disc member and the means for retaining and releasing the member in operative relationship. The clamping member in this figure is shown in released position. 60

Figure 6 represents an end elevational view of the permanent hair waver disclosing the movable discs member in clamped operative relationship with strands of hair. 65

Figure 7 illustrates a fragmentary view 70 of the clamping means and members connected with the curling pin and sleeve portion thereof.

Figure 8 represents a sectional view of Figure 6 taken along line 8—8. 75

In the permanent hair waver, according to this invention, it is preferred that numerals 1 and 2 designate similarly formed disc members made of any suitable material, such as thin metal, and adapted to be connected together in some proper manner, such as by means of a rivet 3 extending through projections 4 integrally formed with the disc members 1 and 2. Suitable spacing elements 5 are adapted to properly separate the disc members 1 and 2 so as to allow for the free movement of a disc or clamping element 6 therebetween, the clamping member 6 being made of any suitable material and rotatably mounted on the main body portion of the 80 hair pinching member by means of pin 9, located in the insulated disc element 7 made of some material, such as hard rubber or gum, and also having co-operating therewith an auxiliary insulator protection 8 consisting of a leather lining or the like. The 85 movable hair clamping member 6 is adapted to be mounted on a pin element 9, operatively positioned in relationship to the hair pincher members 7 and 8, as above described, and 90

95

Figure 1 illustrates a perspective view of the permanent hair waver disclosing the pincher and hair curling pin in assembled and operative relationship.

Figure 2 represents an elevational view of the permanent hair waver disclosing the general location of the hair pinching disk in assembled relationship with the curling pin. 100

the clamping member 6 is provided with an arm or lever extension 10 by which the hair clamping member may be easily revolved when desired. As clearly disclosed in Figures 5 and 6, the rotatably mounted disc element 6 for clamping the strands of hair together is formed having an inwardly extending slotted portion 11 for co-operating and registering with similarly inwardly extending slotted portions of the disc members 1, 2, 7 and 8. The hair strands are adapted to be projected into assembled relationship within the slotted element 11, after which the disc 6 is turned by means of the lever 15 or arm element 10 to a point as approximately disclosed in Figures 4 and 6. The hair strands, being firmly held in clamped relationship, may be retained in that position for the desired length of time by means 20 of a plurality of tooth-shaped projections 12 formed in the periphery of the clamping member 6 and adapted to be brought into co-operating relationship with a ratchet member 13 and pivotally attached to a disc element 2. Ratchet member 13 is arranged to be retained under tension by means of a resilient element 14 positioned between the two disc members 1 and 2. In order to release the ratchet member 13 from interlocked relationship with the tooth elements 12, a latch member 15 is provided pivotally mounted, as at 16, between the disc members 1 and 2 and formed in such a manner that the ratchet 13 may be easily disengaged from 30 interlocking relationship with the tooth elements 12. It is to be understood that the disc member 6, latch 15, ratchet 13 and resilient member 14 are mounted between the discs 1 and 2 in such a manner that they 35 may move freely therebetween. The disc members 1 and 2 are primarily held in spaced relationship by means of the spacing elements 5. However, as an auxiliary means for retaining these discs in proper relationship to each other, yoke members 17, 18 and 40 19 are provided around the periphery of the disc members 1 and 2 and suitably fastened thereto.

The disc member 1 is preferred, in this invention, to be provided with a slotted portion 20 arranged in such a manner that it may receive in firm interlocked relationship therewith a connecting end 21 of a hair curling pin 22. The connecting end 21 is 45 preferably formed of a disc shape adapted to be easily and detachably slipped into the slotted portion 20 of disc 1. The pin 22 may be made of any suitable material and integrally attached to the element 21 or 50 otherwise, as may be desired, it being understood, however, that the pin 22 and disc element 21 should be firmly fastened together in order that the hair pinching device in general, as described above, may be 55 brought into firm and clamped relationship

with the curling pin 22 primarily by means of a rotatably threaded element 23, the threaded section 24 thereof being adapted to co-operate with threaded portions in the outer end of the curling pin 22. A sleeve member 25, made of any suitable material, is adapted to be loosely mounted over the pin 22 in such a manner that, when the rotatably threaded member 23 is turned, the disc element 21 of the pin 22 will be brought 60 into clamped relationship with a lip element 26 extending from the disc 1, or released from clamped relationship, according to the manner in which the rotatably threaded element 23 is operated. It is to be understood 65 that the loosely mounted sleeve portion may be firmly clamped or released from rigid relationship to the hair pinching device in general by the simple expedient of rotating the member 23 in either direction, the loose 70 sleeve member being held in position between the lip element 26 extending from the disc member 1 and a shoulder portion 27 formed in the member 23.

In operation, this invention provides a 75 hair curler for permanent hair waves which is a great improvement over the existing devices of the like. The hair pincher in general, according to this invention, consists of two main portions between which is 80 mounted a hair strand clamping member, means being positioned between the discs for holding the hair in position for curling or releasing the hair therefrom. The curling pin is not screwed into the hair pinching device, as in ordinary practice, but is detachably slipped into a notch receiving element located on the surface of one of the discs in such a manner that the curling pin may be 85 brought into firm clamped relationship with the hair pincher device or released therefrom, as may be desired. The strands of hair are adapted to extend through the hair pinching disc and encircle a removable sleeve portion surrounding the hair curling pin, after which the hair strands are treated with 90 a suitable preparation for maintaining the hair strands in the form of locks or curls. The hair pincher device in general consisting of various discs is then removed from 95 interlocked relationship with the hair and curling pin by merely releasing the tension on the movable sleeve portion around the pin and slipping the pin from the hair pincher. When the hair clamping disc has 100 been released, the hair pincher device as a whole may readily be removed from or connected with the hair waver, after which it is a simple matter to remove the curling pin and sleeve portion from contact with the 105 hair strand.

Some of the advantages of this invention over the permanent hair wavers ordinarily used are a great saving in the application and removal of the hair pincher and also a great 110

relief from the annoyance due to straining on the hair when the curling pin was being attached and detached from the hair.

Obviously, no objectionable twisting of hair strands are needed in the use of this invention for the reason that the hair pincher and curling pin are attached or detached from each other by a clamping means. It is to be understood that alterations and substitutions may be made in the above disclosure, including the drawings, within the scope of the appended claims without affecting the merits of the invention.

What I claim is:

1. A hair curler comprising a hair pinching member and a curling pin removably attached thereto, suitable openings in the hair pincher through which strands of hair are adapted to pass, rotatable means mounted in the hair pincher for clamping the strands of hair together, a slot and tongue portion in the hair pincher for detachably receiving the curling pin, the strands of hair being adapted to encircle the pin.

2. A hair curler comprising a hair pinching member and a curling pin removably attached thereto, suitable openings in the hair pincher through which strands of hair are adapted to pass, rotatable means mounted in the hair pincher for clamping the strands of hair together, a slot and tongue portion in the hair pincher for detachably receiving the curling pin, the strands of hair being adapted to encircle the pin, a sleeve member loosely mounted on the curling pin for receiving the strands of hair in encircling relationship thereon.

3. A hair curler comprising a hair pinching member and a curling pin removably attached thereto, suitable openings in the hair pincher through which strands of hair are adapted to pass, rotatable means mounted in the hair pincher for clamping the strands of hair together, a slot and tongue portion in the hair pincher for detachably receiving the curling pin, the strands of hair being adapted to encircle the pin, a sleeve member loosely mounted on the curling pin for receiving the strands of hair in encircling relationship thereon, means for clamping the curling pin and sleeve to the hair pincher.

4. A hair curler comprising a hair pinching member and a curling pin removably attached thereto, suitable openings in the hair pincher through which strands of hair are adapted to pass, rotatable means mounted in the hair pincher for clamping the strands of hair together, a slot and tongue portion in the hair pincher for detachably receiving the curling pin, the strands of hair being adapted to encircle the pin, a sleeve member loosely mounted on the curling pin for receiving the strands of hair in encircling relationship thereon, means for clamp-

ing the curling pin and sleeve to the hair pincher consisting of a tension member connected with the curling pin in such a manner that the sleeve and pin may be brought into clamped relationship with the hair pincher 70 or released therefrom, as desired.

5. A hair curler comprising a main body portion, a rotatively mounted disk in the main body portion for clamping a plurality of hair strands together, a curling pin removably attached to the main body portion, suitable openings in the main body portion and the disk member for receiving the strands of hair, the opening in the rotatable disk being adapted to register with the opening in the main body portion when about to receive the strands of hair, tooth shaped elements and suitable cooperating members loosely mounted in the main body portion for holding the disk under desired tension. 80

6. A hair curler comprising a main body portion, a rotatively mounted disk in the main body portion for clamping a plurality of hair strands together, a curling pin removably attached to the main body portion, suitable openings in the main body portion and the disk member for receiving the strands of hair, the opening in the rotatable disk being adapted to register with the opening in the main body portion when about to receive the strands of hair, tooth shaped elements and suitable cooperating members loosely mounted in the main body portion for holding the disk under desired tension, 90 means mounted on the main body portion for releasing the tension on the disk and allowing it to return to the normally open position.

7. A hair curler comprising a main body portion, a rotatively mounted disk in the main body portion for clamping a plurality of hair strands together, a curling pin removably attached to the main body portion, suitable openings in the main body portion and the disk member for receiving the strands of hair, the opening in the rotatable disk being adapted to register with the opening in the main body portion when about to receive the strands of hair, tooth shaped elements and suitable cooperating members loosely mounted in the main body portion for holding the disk under desired tension, 105 means mounted on the main body portion for releasing the tension on the disk and allowing it to return to the normally open position, a lever extension on the disk for convenient operation thereof.

8. A hair curler comprising a main body portion, a rotatively mounted disk in the main body portion for clamping a plurality of hair strands together, a curling pin removably attached to the main body portion, suitable openings in the main body portion and the disk member for receiving the strands of hair, the opening in the rotatable 125

disk being adapted to register with the opening in the main body portion when about to receive the strands of hair, tooth shaped elements and suitable cooperating members 5 loosely mounted in the main body portion for holding the disk under desired tension, means mounted on the main body portion for releasing the tension on the disk and allow-

ing it to return to the normally open position, a lever extension on the disk for convenient operation thereof, means mounted on the main body portion for acting as stop limits on the movable members. ¹⁰

In testimony whereof I affix my signature.

CARL ZIMMER.
